UNITED STATES PATENT OFFICE.

EDGAR R. CREAMER, OF CONNERSVILLE, INDIANA, ASSIGNOR TO THE GEORGE R. CARTER COMPANY, OF CONNERSVILLE, INDIANA, A CORPORATION OF INDIANA.

MACHINE FOR MAKING PAPER FILLERS.

Application filed March 12, 1927. Serial No. 174,841.

This improvement relates to a machine for making paper fillers for use in various kinds of devices including moulding devices, such as those described in Letters Patent to Bolender and Creamer #1,387,639.

In a general way the machine is adapted to operate upon a sheet of paper, preferably Japanese crepe paper, and mechanism is provided for compressing the side edges of the paper towards its central line of travel thereby forming folds in the paper. This paper having a coating of adhesive substance will be readily thereafter compressed into such shape and the folds will be held compactly together forming a tape or tube which can be twisted and turned into various shapes and positions without difficulty. The tube itself is described in a copending application of Bolender and Creamer filed February 5th, 1927, Serial No. 166,123.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a side elevation of the machine. Fig. 2 is a plan view. Fig. 3 is an elevation of the feed and creasing rolls. Fig. 4 is a sectional view taken on the line 4—4 of Fig. 1. Fig. 5 is a view taken on the line 5—5 of Fig. 1. Figs. 6 and 7 are detail views of the worm gear mechanism for operating the disk. Figs. 8 and 9 are detail views of the adjusting device for one of the shafts. Fig. 10 is an elevational view taken from one side of Fig. 2, i. e. the top part of that figure. Fig. 11 is a diagrammatic view of the sheet of paper showing the pleats or crimps.

The base of the machine is indicated by 1, on which is mounted the supporting frame 2, formed with guide-ways 2^a thereon, which are associated with the sliding members 3 and these sliding members 3 support the operating device for folding the paper sheet. These heads 3 are shown slidably mounted in Figs. 1 and 2. There is a nut or

sleeve 4 projecting from each of the heads 3 through which is screwed the screw 5. The screw shaft 5 is mounted to turn in the frame and the turning of this screw 5 by the hand wheel 6 will cause the nuts to slide along the screw and as there are employed right and left hand threads the two heads 3 will be moved so as to approach more closely together or be separated, thereby providing the adjustment for the passageway for the sheet of paper. There is an operating shaft 7 associated with each head (see Figs. 1 and 6) and this shaft 7 is supported in bearings at its upper and lower ends as more fully explained hereinafter. This operating shaft has secured thereon a worm-wheel 9 which is in mesh with a worm 10. In order to permit the heads 3 to be moved outwardly or inwardly the worms 10 are keyed to the driving shaft 11 and there is a yoke 12 for connecting the shafts 7 and 11 in a way to insure the gear and worm remaining in proper mesh when the shaft 7 is moved or tilted as will be hereinafter explained. This yoke 12 (see Fig. 7) is loosely mounted on the shaft 7 and is formed with bearings which extend around the worm shaft 11 (see Fig. 6). The pairs of disks marked 13 and 14 are the instrumentalities for forming the folds in the paper and these disks are mounted on the shafts 7, there being a disk for each shaft. These disks 13 and 14 are formed with hub portions 13^a and 14^a projecting from the center of the disks and the disks are so mounted that the disks themselves will overlap and the hub portions will lie in proximity one to the other so as to form a passageway marked 16 (see Fig. 2). It is desirable to tilt one of the disks, preferably the lower disk, (see Fig. 1) so that the exit of the passageway will present a freedom for the movement of the folded paper after it has been operated on by the hubs of the two disks, it being understood that one disk has the hub on its upper surface, and the other disk has the hub on its lower surface. In order to enable one of the disks to be tilted the set screws 15 are employed (see Figs. 1, 8 and 9) so that by adjusting the set screws the shaft 7 can be slightly tilted which will cause the disk supported thereby to be tilted and during its movement the gear 9 and worm 10 will be kept properly in mesh by the yoke structure indicated by 12. There is a

stationary guide 17 (Fig. 2) which extends in close proximity to the periphery of the disks 13 and 14 and the sheet of paper is thereby guided into the proper path to insure its entering the passageway 16 in such a manner that the edges of the hubs of the two disks can compress the side edges of the sheet of paper toward the central line thereof thereby forming a multiplicity of small 10 folds and when the hubs 13^a and 14^a are acting upon this sheet of paper the paper is also held against displacement by the flat surface of the disks 13 and 14. As these disks are rotated in the direction indicated by the arrows (Fig. 2) this passageway is in effect formed by four movable walls, two of which are the flat surfaces of the disks and two the surfaces of the hubs. The motor shaft 18 (Figs. 1 and 2) is properly supported by 15 20 sub-base 1^a of the machine and this motor shaft has secured to its outer end a worm 19 which is meshed with the worm-wheel 20 secured to one end of the driving shaft 11 thereby the motion is transmitted through 25 30 said shaft to the worms 10 and the worm wheels 9 herebefore referred to. This motor shaft has also a worm 21 secured thereto intermediate its ends which is in mesh with a worm-wheel 22 mounted on one end 35 40 of a cross shaft 22^a which is supported by the sub-base 1^a. This cross shaft 22^a carries the upper roll 23 hereinafter referred to and at its opposite end is geared to the lower roller shaft 22^b which carries the roll 24. These 45 50 rolls are indicated by 23 and 24 and are what are termed the forming rolls. One roll has an annular groove and the other a tongue projection thereby giving to the paper filler the desirable form for its use in mouldings hereinbefore referred to. The cross shaft 22^b has on its extreme end a disk 28 and on the flat surface of that disk there is preferably a fibre disk 29 which engages that surface. This fibre disk 29 is slidably mounted 55 60 on the shaft 31 which shaft in turn is supported in bearings that are in turn supported by the bracket 1^b (Fig. 10). A screw 31^a passes through the yoke 30 which is connected to the fibre disk 29 and by turning 65 70 this screw 31^a the fibre disk will be adjusted to transmit the necessary movement to the shaft 31. This shaft 31 has at its opposite end (Fig. 2) a worm 32 which is in mesh with a worm-wheel 33 which is secured to a 75 80 cross shaft and at the opposite end of this cross shaft there is a gear 34 which is in mesh with a gear 35 secured to an upper roller shaft. As indicated in Fig. 3 the lower roller shaft carrying the gear 34 and the 85 90 upper shaft carrying the gear 35 have near the center thereof two rolls which are formed preferably to crease the paper. The small ridges formed in these rolls accomplish that purpose but it is not essential to the operation of the machine that these ridges be em-

ployed. These rolls also feed the paper sheet to the passageway 16 and the machine is so geared that these rolls will operate at a slightly faster rate than the disks 13 and 14 so as to prevent the paper sheet from being unduly stretched when the edges of the paper sheet come in contact with the hub portions herebefore referred to and forming rolls 23 and 24 are geared so that these rolls will operate slightly faster than the above mentioned rolls to insure the paper sheet passing through the passageway 16 without being buckled or barred.

From the foregoing description it will be clear that the paper sheet is preferably creased slightly by the creasing rolls and likewise fed by them through the guide 17 to a point where the hubs of the disks 13 and 14 will begin to operate upon the paper sheet and when the sheet reaches the narrowest portion of the passageway the folds will be formed and the folded article will be properly held in that passageway, and the folds will be inclined to be held together by the adhesive substance which is applied to the sheet of paper prior to it being fed into the machine and this folded sheet will then pass into the groove formed in one of the rollers 23 or 24 and these rollers will then complete the feeding of the article while acting upon the folded sheet to give it a contour such as described clearly in the copending application heretofore referred to. As heretofore explained these two disks 13 and 14 are slidably mounted so that the necessary variation in the width of the passage can be made by operating the hand-wheel 6 and the proper clearance may be obtained by tilting one of the shafts 7 and when this is done there is minimized the danger of the article adhering to the face of the disk and thereby tending to throw the article out of the proper path of movement necessary to reach the groove formed in one of the forming rolls. Nothing herein is intended to waive any of the patentable features of the copending application Serial No. 166,123.

Without further analysis, the foregoing will so fully reveal the gist of this invention that others can, by applying current knowledge, readily adapt it for various utilizations by retaining one or more of the features, that, from the standpoint of the prior art, fairly constitute essential characteristics of either the generic or specific aspects of this invention and, therefore, such adaptations should be, and are intended to be, comprehended within the meaning and range of equivalency of the following claims:—

Having thus revealed this invention, I claim as new and desire to secure the following combinations and elements, or equivalents thereof, by Letters Patent of the United States:

1. In a machine for folding a sheet of

- paper into a filler, a plurality of rotating members arranged in such relation as to form a passageway between the rotating surfaces of said members, the plane of one of said members being inclined to the plane of the other, and means for feeding said sheet of paper through said passageway.
2. In a machine for folding a sheet of paper into a filler, a plurality of rotating members arranged in such relation as to form a passageway between adjacent surfaces of said members, the horizontal plane of one of said members being inclined to the horizontal plane of the other, rolls for pushing the paper in one direction at one side of said passageway and means for pulling the article in the same direction at the other side of said passageway.
3. In a machine for forming a filler from a sheet of flexible material, a plurality of rotating members arranged in such relation as to form a passageway between the rotating surfaces, the said members forming movable walls for said passageway and one of said movable walls being tilted in its relation to one of the other walls to insure the proper withdrawal of said article from said passage.
4. In a machine for folding a sheet of paper into a filler, the combination of rotating members having vertical and horizontal projecting walls forming a passageway, two of the vertical walls of same being capable of compressing the sheet into pleats, while the other walls forming said passage engage and hold the pleats during the period of time the pleats are being formed and means for feeding said sheet through said passageway.
5. In a machine for folding a sheet of paper into a filler, the combination of rotating members having projecting walls arranged transversely one to the other forming a passageway, two of the walls of same being capable of compressing the sheet into pleats while the other walls of said passage engage and hold the sheet against displacement during the period of time the pleats are being formed, an adhesive substance being applied to the surfaces of the sheet of paper prior to the pleats being formed therefrom and means for feeding the article from the passage.
6. In a machine for forming a filler from a sheet of paper, a plurality of rotating members arranged in such relation as to form a passageway between the rotating surfaces, said members forming movable walls for said passageway, the sheet of paper being compressed into folds by said walls, means for creasing the sheet of paper and for feeding same to said passageway.
7. In a machine for forming a filler from a sheet of paper, a plurality of rotating members arranged in such relation as to form a passageway with rotating walls, two of the walls in said passageway formed by said rotating members being spaced sufficiently apart gradually to compress the edges of the sheet of paper towards a central point thereby forming pleats in such sheet, means for creasing said sheet of paper prior to its being operated upon by said walls and means for pulling said article away from said passageway.
8. In a machine for forming a filler from a sheet of paper, a plurality of rotating members, same being spaced apart to form a passageway having rotating surfaces in said passageway, said members having additional surfaces contacting against the top and bottom of said sheet for holding same against displacement while it is being acted upon by said first mentioned surfaces.
9. In a machine for compressing a sheet of paper into a pleated filler tube, the combination of feeding devices with compressing members spaced apart to form a passageway having movable walls converging at a central point to compress the sheet into a multiplicity of pleats, the greatest compression being exerted at said central point with additional contacting members for holding the said sheet against displacement while being compressed as aforesaid.
10. In a machine for compressing a sheet of paper into a pleated filler tube, the combination of feeding devices with a plurality of revolving compressing members spaced apart to form a passage way with movable walls, one set of walls being properly spaced to draw the edges inwardly towards a central point and another set of movable walls so placed as to prevent the sheet from being displaced during the formation of the pleats.
11. A machine for forming pliable fillers from a sheet of flexible material combining rotary members for compressing the material into pleats; driving means therefor; rolls for feeding the sheet material to said rotary members; a variable speed transmission for driving said rolls at a selected speed slightly faster than said rotary members; forming rolls, and means for driving said forming rolls at a slightly greater speed than said rotary members.

In witness whereof, I have hereunto subscribed my name.

EDGAR R. CREAMER.
